DANCING DOLL

Filed July 19, 1949

UNITED STATES PATENT OFFICE

2,592,669

DANCING DOLL

Obie V. Dyer, Tulare, Calif.

Application July 19, 1949, Serial No. 105,600

2 Claims. (Cl. 46—138)

1

This invention relates to toy devices, and more particularly to a novel dancing doll device.

A main object of the invention is to provide a novel and improved dancing doll toy which is very simple in construction, very easy to operate, and which is very entertaining, especially for children.

A further object of the invention is to provide an improved dancing doll toy which is very inexpensive to manufacture, which involves only a few parts, which is very rugged in construction, and which is adapted to hold the interest of children over long periods of time.

Other objects and advantages of the invention will become apparent from the following description and claims, and from the accompanying drawings, wherein:

Figure 1 is a front elevational view of a mechanical dancing doll toy constructed in accordance with the present invention;

Figure 2 is a side elevational view of the dancing doll toy of Figure 1;

Figure 3 is a side elevational view of a modified form of dancing doll toy adapted for manual operation;

Figure 4 is a cross-section detail view taken on line 4—4 of Figure 2;

Figure 5 is a fragmentary cross-sectional detail view taken on line 5—5 of Figure 4.

Referring to the drawings, and more particularly to Figures 1, 2, 4 and 5, 11 designates a base member which may be made of any suitable material such as wood, plastic, metal, or the like, and may have any desired shape. Secured to base member 11 is an upstanding, U-shaped bracket 12. Secured rigidly to the top portions of the arms 13 and 14 of the bracket 12 is a first horizontal shaft member 15. Rotatably mounted in the arms 13 and 14 below shaft 15 is a second shaft 16. Designated at 17 is a spiral clock spring wound on shaft 16 whose inner end is secured to said shaft and whose outer end is secured to a pin 18 carried on arm 14. Shaft 16 carries a winding key 19 outwardly adjacent arm 13 and carries a large gear 20 which meshes with a pinion gear 21 carried on a shaft 22 rotatably mounted in arms 13 and 14 below shaft 16. Shaft 22 carries an escapement wheel 23. Rotatably mounted in the arms 13 and 14 below shaft 22 is a horizontal bar member 24 carrying a U-shaped escapement member 25 whose teeth are interengagable with the teeth of escapement wheel 23 in the usual manner whereby bar member 24 may be oscillated by the cooperation of escapement member 25 with escapement wheel

2

23 as shaft 22 is rotated responsive to the unwinding of clock spring 17.

Designated at 26 is an upstanding resilient wire member secured to shafts 15 and 16 by the coiled turns 27 and 28 thereof, the lower end of said wire member being anchored to bracket arm 13 at 29. A first horizontally disposed wire 30 has one end secured to the upper end of the vertically disposed wire 26. A second horizontally disposed wire 31 is arranged in end to end spaced relation with respect to the other end of the first horizontally disposed wire 30 and spaced above the latter wire. A riser 33 is interposed between the adjacent ends of the wires 30 and 31 and is connected thereto. A hook 32 is formed on the other end of the wire 33. Bar member 24 is formed with an upstanding lug 34 and rigidly secured to said lug is an upstanding wire rod 35 whose top end is formed with an eye 36 looped over wire 30 of the wire member 26, as shown in Figure 2, and being engageable with the riser 33. When no weight is secured to hook 32, the upward resilient force exerted by wire 30 on the eye 36 holds the wire rod 35 against movement and locks the escapement member 25 with respect to escapement wheel 23. When a weight, such as the articulated doll shown at 37, is suspended from the hook 32, the wires 30 and 31 are deflected downwardly, releasing eye 36 and allowing the escapement bar 24 to be oscillated by the escapement mechanism. This oscillates rod 35 back and forth, causing eye 36 to strike riser 33 intermittently whereby wire 31 is vibrated. The vibrations of wire 31 are transmitted to the articulated doll 37, causing the doll to jerk with each vibration, and imparting a dancing movement thereto.

As shown in Figures 1 and 2, the doll 37 is freely jointed at various portions thereof, as shown at 38, whereby the various members of the doll may freely swing with respect to each other. The feet of the doll, shown at 39, engage the base member 11, whereby vertical oscillations of the doll cause said feet to intermittently strike the base member, causing the knee joints of the doll to bend.

In operation, the key 19 is rotated to wind up the spring 17, after which the escapement mechanism produces the above-described oscillations of rod 35 and the vibrations of the wires 31 and 33, causing the doll to dance until spring 17 is substantially unwound.

In the embodiment of Figure 3, a vertical post element 40 is secured to the base 11 and a resilient wire member 41 is engaged at its upper and

lower portions through the post member 40 in the manner illustrated. The wire member 41 is formed with a forwardly-extending top arm 42 terminating in a hook 43. The doll 37 is suspended from the hook 43 with its feet 38 engaging the base and can be made to dance by manually oscillating the top arm 42 in a vertical plane.

While certain specific embodiments of dancing doll toy devices have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A toy dancing doll comprising a base member, an upstanding bracket positioned upon said base member adjacent one end thereof and secured thereto, a vertically disposed wire superimposed upon the upper end of said bracket and having the lower end secured thereto, a first horizontally disposed wire having one end secured to the upper end of said vertically disposed wire, a second horizontally disposed wire arranged in end to end spaced relation with respect to the other end of said first horizontally disposed wire and spaced above the latter wire, a riser interposed between the adjacent ends of said first and second horizontally disposed wires and connected thereto, a hook positioned on the other end of said second horizontally disposed wire and secured thereto, a spring motor mounted within said bracket, an upstanding rod having its lower end operatively connected to said spring motor and having its upper end loosely connected to said first horizontally disposed wire and engaging said riser, and an ar-

ticulated doll positioned underneath said hook and dependingly supported therefrom, the other end of said doll engageable with said base member.

5 2. A toy dancing doll comprising a base member, an upstanding bracket positioned upon said base member adjacent one end thereof and secured thereto, a vertically disposed wire superimposed upon the upper end of said bracket and having its lower end secured thereto, a horizontally disposed wire having one end secured to the upper end of said vertically disposed wire, a hook positioned on the other end of said horizontally disposed wire and secured thereto, a spring motor mounted within said bracket, an upstanding rod having its lower end operatively connected to said spring motor and having its upper end loosely connected to said horizontally disposed wire and engaging an abutment formed on said wire intermediate the ends of the latter, and an articulated doll positioned underneath said hook and dependingly supported therefrom, the other end of said doll engageable with said base member.

25 OBIE V. DYER.
